HEATING APPARATUS

Filed May 29, 1926

UNITED STATES PATENT OFFICE.

THOMAS JEFFERSON PEACE, OF NEVADA, MISSOURI.

HEATING APPARATUS.

Application filed May 29, 1926. Serial No. 112,684.

This invention relates to an improved heating apparatus and it has more particular reference to one which is especially designed for heating air to be conducted in a somewhat conventional manner through appropriate piping and registers to the rooms of a domestic dwelling.

The invention has reference, broadly, to an improved casing adapted to accommodate, for instance, gas burners, each of which is provided with its own conducting pipe for the products of combustion, this being so arranged as to provide a tortuous passage and radiating surfaces for the contacting air, whereby it will be effectively heated and distributed into the room.

It is my principal object to generally improve upon structures of this class by providing one including novel details arranged in a novel manner for subjecting the air to an exceptionally efficient course, so that it will be positively heated before escape into the room.

The invention is illustrated in the accompanying drawings in which:—

Figure 1 is a view showing the invention with a portion broken away and shown in section disclosing internal construction more plainly.

Fig. 2 is a central vertical section through the same.

Fig. 3 is a horizontal section.

Referring now to the drawings in detail, it will be seen that the reference character 12 designates a rectangular casing having a frusto-conical top 13, flues 14, and air conducting pipes 15. At the bottom are appropriate draft regulator doors 16 for the burners 17. It will be noted that I employ three burners, one for each side wall and one for the front wall. Thus, it becomes necessary to form three separate compartments for these burners. It follows that on each burner equipped wall, we find a metal burner housing 18 which is of somewhat elongated form and provided with a frusto-conical top wall. Then extending upwardly from the flattened apex portion of the top wall is a combustion and gas conducting pipe or tube 19.

Referring to Fig. 2, it will be seen that the tube extends upwardly in close proximity to the four walls of the casing, thus providing a plurality of superposed substantially square convolutions, and it com-

municates at its top with its respective flue. It will also be noticed from this figure that inasmuch as there are three upwardly extending tubes 19, it is necessary to so bend the coils or convolutions as to arrange the three different sets in nesting or interfitting relation. The manner of accomplishing this is well known in this particular art, and is shown plainly in Fig. 2, and a specific discussion of this feature is not necessary.

An appropriate cold air pipe (not shown) is connected to one of the side walls adjacent the bottom and the upwardly passing air comes into direct contact with the coils of the several sets of tubes, thus taking up the heat by way of radiation and absorption, and escaping through the usual hot air conducting conduit.

It is obvious that the entering cold air never takes up any of the products of combustion or gases, and while I am aware of the fact that this feature of construction is not new, it is believed that the particular arrangement of the heat conductors is new. Therefore, the alleged novelty of the invention will be clear upon considering the accompanying claim.

While I have shown and described the preferred embodiment of the invention, it is to be understood that minor changes in the shape, size, and arrangement of the details may be resorted to within the field of invention covered by the claim.

Having thus described my invention, what I claim as new is:—

In a heating apparatus of the class described, a substantially rectangular casing, a hot air conducting pipe connected with the top of the casing, a plurality of burners disposed in the lower portion of the casing and associated with said front and side walls thereof, a substantially frusto-conical jacket for each burner, and a combustion and gas conducting tube connected with the flattened apex portion of each jacket, these tubes being coiled upwardly through the casing and the branches of the coils being disposed in proximity to the interior of the walls of the casing, and each tube being connected at its top with a flue, the coils of the several sets being arranged in nested relation.

In testimony whereof I affix my signature.

THOMAS JEFFERSON PEACE.
